UNITED STATES PATENT OFFICE.

MICHAEL BLOCK, OF SOUTH BOSTON, MASSACHUSETTS, ASSIGNOR TO AMERICAN CAN COMPANY, OF NEW YORK, N. Y., A CORPORATION OF NEW JERSEY.

CONTAINER.

Application filed April 27, 1921. Serial No. 465,024.

To all whom it may concern:

Be it known that I, MICHAEL BLOCK, a citizen of the United States, residing in South Boston, in the county of Suffolk and 5 State of Massachusetts, have invented a new and useful Improvement in Containers, of which the following is a specification.

This invention relates in general to containers, and more particularly to that class 10 of containers adapted for the display of crackers or other contents, and having for that purpose glass sections in a side thereof. In the use of such containers it often becomes necessary to ship them empty, as 15 from a grocer to a baker, and it has been a common experience to have the glass fronts broken in transit.

It is a principal object of my invention to provide means whereby the glass section of 20 the container front may be raised inside the container and held in protected position while being handled empty.

A further object of the invention is the provision of means for accomplishing this 25 purpose which add but slightly to the cost of the container and which do not in any way detract from the pleasing appearance thereof, being both simple in construction and effective in service.

30 Numerous other objects and advantages of the invention will be apparent as it is better understood from the following description, which, taken in connection with the accompanying drawings, discloses a preferred embodiment thereof.

Referring to the drawings:

Fig. 1 is an elevational view of a front section of a container embodying my invention.

40 Fig. 2 is an enlarged vertical section taken substantially on the line 2—2 of Fig. 1.

Fig. 3 is an enlarged elevation of the interior of the container front shown in Fig. 1, and showing the retaining catch both in 45 operative and raised positions, the latter being indicated in dotted lines.

Fig. 4 is an enlarged detail taken substantially on line 4—4 of Fig. 3.

Fig. 5 is an enlarged detail taken substantially on line 5—5 of Fig. 3.

Upon the drawings, which illustrate a preferred embodiment of the invention, I have shown a container front 11 having therein a window or display glass 12 and an 55 inset portion 13, designed to lend attractive-

ness to the appearance of the container, and the window permitting the display of the contents. The front 11 is shown as integral with the side walls 14, and as being engaged by upturned flanges 15 and 16 in the bottom section. The top or cover of the container is hinged at the rear in a manner not shown and has a depending front flap 17, having a curled flange 18, being thus adapted to frictionally engage the upper part of the front 60 section 11 whereby it is held in closed position, and being also adapted to be easily opened by applying upward pressure to the flange or bead 18. The front section is 65 preferably formed from a single piece of metal, in which case the front and side walls are or may be made of said single piece; and about the peripheries of the inset portion 13 and the window 12 are rounded edges 19 and 21, which, with a bead or corrugation 22 stamped outwardly in the lower 70 part of the section, are adapted to add to 75 the sightliness of the container.

Referring to Figs. 2 and 3, the internal arrangement of the container front may be 80 observed. The lower part 23 is arranged in the form of a door hinged by means of alternate segmental beaded portions 24 and 25 (Fig. 3) in the door and in the separate strip portion *a*, attached to the front, and 85 having extending therethrough a rod or pin 26. In this door the glass section 12 is set, being held in place by overturned flanges 27 of the metal part of the door. The door is normally held in its down or closed position by means of upstanding projections 28 which are formed by indenting inwardly the material of the container bottom, and are 90 of such height as to permit the lower portion 29 of the door to be forced past them to 95 closed position and yet to be held firmly in that position, positive pressure being required to again force the door inwardly to permit movement of it to its protected position. The number and exact form of these 100 projections is, of course, immaterial, it being merely essential that they be of such height as to provide proper frictional engagement with the door.

The retaining means employed at the top 105 of the container will now be described, particular attention being directed to Figs. 3 and 4. A wire member 31 is pivotally secured at one end beneath the guard or holding member 32 and has near the opposite 110

end a U-shaped bend forming an inwardly projecting catch 33 adapted to be projected behind the edge 29 of the door when it is raised to its upper or protected position. 5 The upper flange 34 of the container front is turned to horizontal position and the horizontal portion turned back upon itself at 10 35 and within a portion thereof is engaged a strengthening strip 36 extending around the line of bend between the vertical front and the horizontal flange. In this flange, and extending through both the folds thereof and the strengthening strip 36 is an aperture 15 through which the catch 33 may be projected, the member 31 being so positioned with relation to this aperture that in forcing the catch 33 into operative position the front portion 37 of the catch comes into 20 rather tight engagement with the side wall 25 of the aperture. In this manner the catch is positively held in operative position and yet may be freely moved to and from that position to engage or disengage the raised door at will. It will be noted that this retaining member is positioned beneath the 30 container cover and is not visible when the container is closed. It, therefore, does not in any way mar the appearance of the container and is of such small size that even when projected into the interior thereof it does not decrease the capacity.

It is thought that the invention and many of its attendant advantages will be under-

stood from the foregoing description, and it will be apparent that various changes may 35 be made in the form, construction and arrangement of the parts without departing from the spirit and scope of the invention or sacrificing all of its material advantages, the form hereinbefore described being 40 merely a preferred embodiment thereof.

I claim:

1. A display container having a wall formed with a display opening and a continuous closed portion, and a display section having a glass and hingedly connected with said wall and swingable to a position behind said opening and to a protected position behind said closed portion of the wall, and means in the container and movable into 45 and out of engagement with said display section when the latter is in said protected position.

2. In a cracker or like container, a display wall, a display section hingedly connected with said wall and swingable inwardly from its display position to a protected position behind a solid section of said wall, means in the container and projectible through an aperture thereof for holding the display section in protected position and means integral with another wall of said container for holding said display section in display position.

MICHAEL BLOCK.
